(57) CLAIM

The ornamental design for a baseball diamond board, as shown and described.

DESCRIPTION

FIG. 1 is a plan view of a baseball diamond board; and, FIG. 2 is a side plan view of the board.

The broken lines in FIGS. 1 and 2 are included for the purpose of showing portions of the baseball diamond board that form no part of the claimed design.

1 Claim, 2 Drawing SheetsFIG. 1
